DESIGN FOR A DISPLAY STAND

Edwin Gardner Cole and Henry H. Schumacher,
Chicago, Ill.

Application April 6, 1944, Serial No. 113,166

Term of patent 14 years

(Cl. D80—9)

To all whom it may concern:

Be it known that we, Edwin Gardner Cole and Henry H. Schumacher, citizens of the United States, residing in Chicago, in the county of Cook and State of Illinois, have invented a new, original, and ornamental Design for a Display Stand, of which the following is a specification, reference being had to the accompanying drawing, forming a part thereof.

In the drawing:

Fig. 1 is a front perspective view of a display stand, showing our design; and

Fig. 2 is a rear perspective view thereof, on a reduced scale.

We claim:

The ornamental design for a display stand, substantially as shown.

EDWIN GARDNER COLE.
HENRY H. SCHUMACHER.
